TOY AIRPLANE

Sylvester Clark Grady, Chester, N. J.

Application May 25, 1937, Serial No. 144,745

8 Claims. (Cl. 46—78)

The present invention relates to new and useful improvements in toy airplanes and more particularly to improved driving means therefor.

An object of the present invention is to provide a toy airplane having a plurality of propelling units, one or more of which may be successfully brought into operation upon the expenditure of power in another so as to prolong the flight of the toy airplane.

10 A further object of the invention is to provide a toy airplane of the above type wherein the details of construction and arrangement of parts make it possible to afford a light and inexpensive construction.

15 The above and other objects of the invention will in part be obvious and will be hereinafter more fully set forth.

In the drawing:

Fig. 1 is a top plan view showing a portion of 20 the toy airplane with the driving means therefor.

Fig. 2 is a side elevation of Fig. 1 partly in section.

Fig. 3 is a front elevation of Fig. 1.

Fig. 4 is an enlarged perspective view showing the details of the bracket which restrains movement of one or more of the propelling units.

In general, the invention contemplates the provision of three or more propellers having independent shafts which are connected to independent spring driving means. In the illustrated embodiment of the invention, two of the propellers are restrained against movement while the third propeller is in operation. For this purpose, there is employed a bracket which is shiftable relative to the airplane frame and against which the inoperative propellers engage as a stop during the operation of the third propeller. Upon the running down of the spring motor for the third propeller, the bracket is adapted to shift

40 so that it will no longer prevent rotation of the two inoperative propellers, thus permitting the two other propellers to be driven by their respective spring motors. In this way, the flight of the airplane is substantially prolonged.

45 In the accompanying drawing, a toy airplane is illustrated as including a body frame or fuselage 10 having at the forward end thereof three outstanding portions 11, 12, 13. The central propeller 14 is connected to a shaft 15 which is provided with a hooked end 16. The hooked end 16 of the shaft 15 is connected to a spring motor 17 which is secured to a hook 18 mounted on a bracket 19 at the rear of the body frame 10. The shaft 15 is rotatably mounted on the central 50 upstanding portion 12 by means of cleats or

staples 20. A bracket 21 is provided centrally of the ends thereof with looped portions 21a through which the shaft 15 extends. The ends of the bracket 21 and the side portions 21b thereof extend beyond the central upstanding portion 12 on the body frame 10 so that the bracket is free to rotate relative to the shaft 15. A pair of spherical washers 22 are mounted on the shaft 15 between the propeller 14 and the forward end of the bracket 21 so as to maintain the propeller 10 14 at a predetermined distance away from the bracket.

15 Mounted on the side upstanding portions 11, 13 for rotation are shafts 23, 24 which carry propellers 25 and 26 respectively.

The shafts 23, 24 are provided with hooked ends for engagement with independent spring motors (not shown) of the same type described in connection with the shaft 15. A pair of wire stops 27, 27a extend forwardly from the central 20 upstanding portion 12 on the body frame 10. The wire stop 27 is disposed below the front end of the bracket 21 when in a horizontal position, and the wire stop 27a is disposed above the front end of the bracket 21, as indicated in 25 Fig. 3. A coil spring 28 encircles the shaft 15 and bears against the looped portion 21a of the bracket 21 at the forward end thereof and against the front staple 20. The spring 28 tends to normally urge the bracket 21 and shaft 15 in a forward direction as the spring motor 17 becomes unwound. A resilient connection is provided between one of the side portions 21b of the bracket 21 and a pin 29 on the body frame 10. This resilient connection may be in the form of a rubber band 30 which tends to maintain the bracket 21 in a substantially vertical position. In other words, as shown in Fig. 3, the rubber band 30 is stretched.

30 The wire stops 27, 27a extend beyond the front end of the bracket 21 when the spring motor 17 is wound up so as to prevent rotation of the bracket 21 relative to the shaft 15. Thus, the propellers 25 and 26 are also restrained 35 against movement.

40 When the central propeller 14 is released, the unwinding of the spring motor 17 will relieve the tension between the hooks 16 and 18 so that the coil spring 28 will operate to urge the bracket 21 in a forward direction with the shaft 15 and 45 the propeller 14. As the spring motor 17 runs down, the front end of the bracket 21 will be forced beyond the stop wires 27, 27a so that bracket 21 will no longer serve as a stop for preventing rotation of the side propellers 25 and 26. 50 55

- Thus, the stored energy in the spring motors (not shown) for the propellers 25 and 26 will now cause rotation thereof. The bracket 21 will be caused to turn on the shaft 15 so that the side propellers are free to operate and prolong the flight of the airplane. The spring member 30 serves to prevent oscillation of the bracket 21 when it has been turned so that it will not interfere with the free rotation of the side propellers.
- 10 It is to be clearly understood that minor changes in the details of construction and arrangement of parts may be made without departing from the scope of the invention as set forth in the appended claims.
- 15 I claim:
1. In a toy airplane, the combination of a plurality of propelling units, an independent spring motor for each of said propelling units, and means engageable with one of said propelling units for preventing rotation thereof until the substantial expenditure of power in a motor for another of said propelling units.
  2. In a toy airplane, the combination of a plurality of propelling units, an independent spring motor for each of said propelling units, a bracket member engageable with at least one of said propelling units for preventing rotation thereof, and means for mounting said bracket member and for permitting the movement thereof out of engagement with the propelling unit upon the substantial expenditure of power in a motor for another of said propelling units.
  3. In a toy airplane, the combination of a plurality of propelling units, an independent spring motor for each of said propelling units, at least one of said motors being extensible upon the expenditure of the stored power therein, and means associated with said extensible motor for engaging another of said propelling units for preventing rotation thereof, said means being shiftable to disengage the propelling unit upon the substantial expenditure of power in said extensible motor.
  4. In a toy airplane, the combination of a plurality of propelling units, an independent spring motor for each of said propelling units, at least one of said motors being extensible from the expenditure of the stored power therein, a bracket shiftable with said extensible motor and engageable with another of said propelling units, and stop means for holding said bracket in engagement with the propelling unit to prevent rotation thereof, the engagement between said stop means and said bracket being such as to release said bracket from engagement with the propelling unit upon the substantial expenditure of power in said extensible motor.
  5. In a toy airplane, the combination of a central axially shiftable shaft carrying a propelling unit, a spring motor connected to said shaft and extensible upon the expenditure of the stored power therein, a pair of side propelling units, an independent motor for each of said side propelling units, a bracket engageable with the side propelling units, means for mounting said bracket for rotation and for endwise movement with said central shaft, and stop means for holding said bracket in engagement with said side propelling units to prevent rotation thereof, said stop means permitting the rotation of said bracket upon the axial shifting thereof incident

to the expenditure of power in said extensible motor to release said side propelling units.

6. In a toy airplane, the combination of a central axially shiftable shaft carrying a propelling unit, a spring motor connected to said shaft and extensible upon the expenditure of the stored power therein, a pair of side propelling units, an independent motor for each of said side propelling units, a bracket engageable with the side propelling units, means for mounting said bracket for rotation and for endwise movement with said central shaft, stop means for holding said bracket in engagement with said side propelling units to prevent rotation thereof, said stop means permitting the rotation of said bracket upon the axial shifting thereof incident to the expenditure of power in said extensible motor to release said side propelling units, and resilient means operable when said bracket is released from said stop means for preventing oscillation of said bracket whereby to prevent its interference with the side propelling units.

7. In a toy airplane, the combination of a central axially shiftable shaft carrying a propelling unit, a spring motor connected to said shaft and extensible upon the expenditure of the stored power therein, a pair of side propelling units, an independent motor for each of said side propelling units, a bracket engageable with the side propelling units, means for mounting said bracket on said central shaft for relative rotation with respect thereto, a spacing device on said central shaft between the propelling unit thereon and said bracket for causing endwise movement with said shaft when said extensible motor is wound up, stop means for holding said bracket in engagement with said side propelling units to prevent rotation thereof, and means for effecting endwise movement of said bracket with said central shaft when the stored power in said extensible motor is substantially expended, the engagement between said stop means and said bracket being such as to release said bracket from engagement with said side propelling units upon the substantial expenditure of power in said extensible motor.

8. In a toy airplane, the combination of a central axially shiftable shaft carrying a propelling unit, a spring motor connected to said shaft and extensible upon the expenditure of the stored power therein, a pair of side propelling units, an independent motor for each of said side propelling units, a bracket engageable with the side propelling units, means for mounting said bracket on said central shaft for relative rotation with respect thereto, a spacing device on said central shaft between the propelling unit thereon and said bracket for causing endwise movement with said shaft when said extensible motor is wound up, stop means for holding said bracket in engagement with said side propelling units to prevent rotation thereof, and a coil spring operative to effect endwise movement of said bracket with said central shaft when the stored power in said extensible motor is substantially expended, the engagement between said stop means and said bracket being such as to release said bracket from engagement with said side propelling units upon the substantial expenditure of power in said extensible spring motor.
